(57) **CLAIM**

The ornamental design for a debris separator as shown and described.

DESCRIPTION

FIG. 1 is a first perspective view of a debris separator according to a first embodiment of the present invention.

FIG. 2 is a second perspective view of the debris separator of FIG. 1.

FIG. 3 is a front view of the debris separator of FIG. 1.

FIG. 4 is a rear view of the debris separator of FIG. 1.

FIG. 5 is a left side view of the debris separator of FIG. 1.

FIG. 6 is a right side view of the debris separator of FIG. 1.

FIG. 7 is a top view of the debris separator of FIG. 1.

FIG. 8 is a bottom view of the debris separator of FIG. 1.

FIG. 9 is a perspective view of a debris separator according to a second embodiment of the present invention.

FIG. 10 is a second perspective view of the debris separator of FIG. 9.

FIG. 11 is a front view of the debris separator of FIG. 9.

FIG. 12 is a rear view of the debris separator of FIG. 9.

FIG. 13 is a left side view of the debris separator of FIG. 9.

FIG. 14 is a right side view of the debris separator of FIG. 9.

FIG. 15 is a top view of the debris separator of FIG. 9; and, FIG. 16 is a bottom view of the debris separator of FIG. 9. The evenly spaced broken lines in the drawings show portions of the debris separator, which form no part of the claimed design.

1 Claim, 16 Drawing Sheets
